(57) **CLAIM**

The ornamental design for a handle for walk behind appliance as shown and described.

DESCRIPTION

FIG. 1 is a perspective view of a crack sealant dispensing system illustrating a handle for walk behind appliance according to our new design in use;

FIG. 2 is a perspective view of the handle for walk behind appliance shown in isolation;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines illustrate environmental structure and portions of the handle for walk behind appliance that do not form part of the claimed design.

1 Claim, 7 Drawing Sheets
